UNITED STATES PATENT OFFICE.

JOHN M. HANSEN, OF BELLEVUE, PENNSYLVANIA, ASSIGNOR TO THE PRESSED STEEL CAR COMPANY, OF PITTSBURG, PENNSYLVANIA.

DESIGN FOR A STOP FOR DOUBLE DOORS.

SPECIFICATION forming part of Design No. 34,080, dated February 12, 1901.

Application filed January 16, 1901. Serial No. 43,541. Term of patent 14 years.

To all whom it may concern:

Be it known that I, JOHN M. HANSEN, a citizen of the United States, residing at Bellevue, in the county of Allegheny and State of Pennsylvania, have invented and produced a certain new and original Design for Stops for Double Doors, of which the following is a full, clear, and exact description.

In the accompanying drawings, forming part of this specification, I have illustrated my design in Figure 1 in perspective, in Fig. 2 in side elevation, in Fig. 3 in front elevation, and in Fig. 4 in top plan view.

The leading or material features of my design, as shown in the drawings, consist in the back or base plate a, provided with the holes or perforations b, the floor-plate c, extending at substantially right angles from the upper edge of said back or base plate a and terminating at its outer edge in an upturned flange d, a vertical division wall or partition e, rising from the floor-plate c about midway thereof and extending from the rear edge of the back or base plate a to the upturned flange d of the floor-plate c, and a rib f, extending from the back or base plate a, beneath the floor-plate c, to the upper edge of the upturned flange d.

The stop is usually produced by casting.

Having thus described my invention, what I claim as new, and desire to secure by Letters Patent, is—

The design for a stop for double doors, substantially as herein shown and described.

In testimony whereof I have hereunto set my hand this 24th day of December, A. D. 1900.

JOHN M. HANSEN.
